[57] CLAIM

The ornamental design for a multimedia keyboard for personal computer, as shown and described.

DESCRIPTION

FIG. 1 is a front, left side, top perspective view of a multimedia keyboard for personal computer showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a right side elevational view thereof with the support feet in the downward position; and,

FIG. 9 is a rear elevational view thereof.

The cord is shown in broken lines in the views for illustrative purposes only and forms no part of the claimed design.
